UNITED STATES PATENT OFFICE.

MATTHEW A. STEWART, OF NEWARK, NEW JERSEY, ASSIGNOR TO THE MATT STEWART COMPANY, OF MEMPHIS, TENNESSEE, A CORPORATION OF MAINE.

EYELET AND RIVET FEEDING DEVICE.

962,928.

Specification of Letters Patent. Patented June 28, 1910.

Application filed January 7, 1910. Serial No. 536,869.

To all whom it may concern:

Be it known that I, MATTHEW A. STEWART, a citizen of the United States, residing at Newark, in the county of Essex and State 5 of New Jersey, have invented certain new and useful Improvements in Eyelet and Rivet Feeding Devices, of which the following is a specification, reference being had therein to the accompanying drawing.

10 My invention relates to apparatus for automatically arranging the eyelets of a mass so that their flanges or flanged ends may all be like-turned (usually downward) and supplying the arranged eyelets to other devices 15 as fast or as slowly as they may be used or conveyed away by such other devices.

Eyelets varying little in their various dimensions and being usually so thin as to be easily distorted by pressure, it has been found 20 difficult to arrange and feed them automatically, even at a varying rate, without in any case distorting an eyelet or failing to supply them at the desired rate. The ends suggested are reached by providing a receptacle, 25 for a mass of eyelets, having in its wall apertures through which an eyelet can pass only when presented in a predetermined way, and throwing the eyelets against this perforated wall. An eyelet properly turned 30 finding an aperture unobstructed passes through it and is thereafter carried onward in proper position to be used.

In the accompanying drawings, Figure 1 is a plan view of the apparatus. Fig. 2 is 35 a section on the line 2—2, Fig. 1. Fig. 3 is a section on the line 3—3, Fig. 1. Fig. 4 is an enlarged transverse section of a chute seen also in Figs. 1 and 3, an eyelet being shown therein. Fig. 5 is an enlarged horizontal section on the line 5—5, Fig. 2, eyelets being shown in transit. Fig. 6 is a view 40 corresponding to Fig. 4, but showing a modified construction.

In these views, A represents an upwardly 45 open receptacle having its lateral walls rigidly supported in any suitable way, as by brackets B, which in this instance bear also a bearing B' for the lower portion of a vertical shaft C in the axis of the receptacle 50 and having an upper bearing B' supported from the wall itself. The shaft is rotated in any suitable way, as by a pulley B', and to it is fixed a plate D forming the bottom of the receptacle and projecting at D' beyond one side of the latter. The upper sur-

face of the plate is inclined upward about the shaft so that eyelets in the receptacle will tend to move outward from the shaft so far as to be readily affected by centrifugal force. The receptacle wall on the side 60 where the plate projects has in the lower edge of the part toward which the eyelets on the plate move when the latter rotates in the direction of the arrow notches E which allow eyelets to pass singly when their flanged ends rest upon the plate, and this side forms one wall of a chute F which runs along the upper face of the plate and then turns downward at such an angle that eyelets will descend therein by gravity. 65 The opposite walls of the chute are grooved at G to receive the flanges of eyelets H therein, and the distance between the walls is made only slightly greater than the diameter of the eyelet bodies, and usually the 70 chute has no bottom, the eyelets being supported after they leave the rotating plate by the lower walls of the grooves in which the flanges lie, these walls preferably extending inward and having upwardly projecting 75 ribs K, as shown in Fig. 4, along which the eyelets slide with very little friction.

If a mass of eyelets be placed in the receptacle and the plate be rotated continuously 80 at a moderate rate, the eyelets are constantly thrown against the notched portion of the wall, and as often as one turned flange down finds in its path an unobstructed notch it 85 passes through the wall into the chute where, since it still rests upon the rotating plate, it 90 is gently urged toward the inclined portion of the chute by the frictional action between it and the plate. The eyelets which do not thus pass through the wall are deflected thereby and carried around again and again, 95 those not having their flanged ends downwardly turned being often turned until they assume that position, which they then tend to retain owing to the greater diameter of that end.

If the size of the apparatus and the number of notches be suitable, a surplus of eyelets will be maintained in the chute, no matter how fast they may be used or discharged 100 at its lower end; and if at any time the entire bottom of the chute be covered no harm results for no eyelet of the mass in the receptacle finds an unobstructed notch and hence all go on until the removal of one or 105 more from the chute leaves space for more 110

to enter. The feed is thus self regulating, the eyelets being fed as fast as they may be needed and no faster, and no eyelet is ever subjected to material pressure in any direction. For still further lessening the friction of the eyelets upon the chute, I sometimes support them on a single central rib J, as shown in Fig. 6, and in such case it is obvious that the eyelet cannot tilt.

10 For convenience the bodies to be fed have been termed eyelets, although they may be considered as tubular rivets, and it is plain that so far as the operation of this device is concerned the bodies to be arranged in 15 proper position and fed may be non-tubular rivets or the like bodies the length of which is not greatly in excess of their diameters.

10 The chute is preferably detachable and made of two parallel plates, which in this 20 instance are shown as spaced apart by means of short tubes L through which pass screws M binding the plates together. Slight variations in the width of the chute may be secured by using longer or shorter tubes, and 25 if desired the whole chute may be replaced by one adapted for eyelets or rivets of materially different dimensions, the rest of the apparatus being unchanged.

For illustration I have shown the side 30 walls of the receptacle as extending down alongside the margin of the greater part of the rotating plate, but this is not essential, nor is the construction invariable in various other respects.

35 What I claim is:

1. In apparatus of the class described, the combination with a rotary horizontal plate adapted to engage eyelets by friction only, of a bottomless chute in close proximity to 40 the surface of the plate, crossing a portion of its upper surface, and provided on one side with apertures through which eyelets and the like lying on the plate may pass only when properly positioned, and means 45 for retaining upon the plate such eyelets as fail to pass through said apertures.

2. In apparatus of the class described, the combination with a horizontal rotary plate adapted to engage eyelets by friction only, 50 of a bottomless chute crossing a portion of the plate's upper surface, inclined downward beyond the plate's margin, and having one wall provided with apertures, above the plate, adapted to allow eyelets to pass singly 55 when properly positioned, and means for retaining the eyelets upon the plate until they pass through said apertures.

3. The combination with an eyelet chute having in one wall apertures through which eyelets may pass singly when turned into 60 a predetermined position, and means for throwing eyelets by centrifugal force into positions whereby they may be carried against the side provided with said apertures.

4. The combination with a rotary horizontal plate adapted to engage eyelets by friction only, of a bottomless chute crossing a part of the plate's upper surface and having in that portion toward which articles 70 upon the rotating plate move apertures adapted to allow eyelets and the like to pass when they are properly positioned, said chute being downwardly inclined from the margin of the plate, and means for supporting the 75 advancing eyelets in the inclined portion of the chute.

5. A chute for eyelets and the like having parallel vertical walls at a distance from each other slightly greater than the diameter of the bodies of the articles to be carried and further having below a narrow longitudinal, article supporting flange provided with an upstanding rib adapted to hold such articles just below the walls which 85 guide their bodies.

6. The combination with a rotary plate adapted to engage eyelets by friction only, of a fixed wall for retaining articles upon the plate, and a deflecting wall crossing a 90 portion of the upper surface of the plate provided with apertures, adapted to permit eyelets and the like supported by the rotating plate to pass out when they are turned into a predetermined position, and a bottom- 95 less chute without the wall in position to receive the eyelets and direct their course while they are frictionally urged onward by the portion of the plate without said wall.

7. In eyelet feeding apparatus, the combination with an approximately horizontal rotary plate, of a fixed wall dividing the surface of the plate into unequal segments and provided with notches, in its lower edge, adapted to allow eyelets to pass singly but 105 only when turned to predetermined position, and means for preventing eyelets from passing off the margin of the larger segment.

In testimony whereof I affix my signature in presence of two witnesses.

MATTHEW A. STEWART. [L.S.]
